FORNIA

HYDRAULIC CASING PERFORATOR

Application filed May 5, 1931. Serial No. 535,188.

Our invention relates to devices adapted for operation within tubular members, and relates particularly to a hydraulically actuated device of this character which may be employed to perforate the wall of a tubular member, such as a well casing.

For the purpose of perforating the liner or drill casing within a well, perforating devices are employed having cutters which are forced outwardly through the cylindrical wall of the tubular member forming the liner or casing. Owing to the extremely heavy force which must be employed to force the cutter or tool through the wall of the tubular member, the tubular member is often deformed or made egg-shaped so that it is afterward difficult to place other well members or devices, such as pumps or screens, within the tubular members which have been deformed as a result of the perforating operation.

Our invention comprehends a perforating device which will accomplish perforation of a tubular member from the interior thereof, with a minimum distortion of such tubular member. The invention also comprehends a simple form of hydraulically actuated means for forcing the tools, such as perforating cutters, outwardly through an operating engagement with the tubular member and for subsequently retracting the tools so that the perforator may be moved to another position of operation. In the preferred form of this invention the control of the hydraulically actuated means is accomplished through a member which extends to the exterior of the tubular member, such as to a point above the upper end of the well structure.

It is an object of the invention to provide a perforator having a body adapted to be suspended and substantially centralized within a tubular member of the character above described, a plurality of cutters movably supported in spaced circular arrangement, and simple, powerful, and effective hydraulic means for usefully operating the cutters.

A further object of the invention is to provide a perforator of the above character having a fluid line extending therefrom to a point of pressure fluid supply, and a control means associated with the perforator for control-

ling the inward and outward movement of the cutters.

A further object of the invention is to provide the above set forth control means in the form of a simple valve having connected thereto a part extending to the surface of the ground, whereby the valve may be actuated to control the introduction of fluid under pressure to the hydraulic cutter operating means whereby to selectively produce projection and retraction of the cutters.

A further object of the invention is to provide a perforator of simple and rugged construction which may be economically manufactured, and it is a further object of the invention to provide in a perforator of the above character a body structure forming a plurality of cylinders extending radially or diametrically at different angles, pistons operative within said cylinders for supporting the cutters in operative position, and means for selectively delivering fluid under pressure to the rear or front ends of the pistons whereby to produce the desired outward and inward movement of the pistons and the cutters thereto attached.

It is a further object of the invention to provide a perforating tool equipped with a plurality of projectable cutters, there being means for normally holding the cutters in retracted position.

Further objects and advantages of the invention will be made evident throughout the following part of the specification.

Referring to the drawings, which are for illustrative purposes only,

Fig. 1 is a view, partly vertically sectioned, showing a preferred embodiment of our invention in a tubular member, such as well casing, to be perforated.

Fig. 2 is an enlarged fragmentary cross section on a plane represented by the lines 2—2 of Figs. 1 and 3.

Fig. 3 is an enlarged, vertically sectioned view on a plane represented by the line 3—3 of Fig. 2.

Fig. 4 is an enlarged cross section on a plane represented by the line 4—4 of Fig. 1, showing a simple form of cylinder and piston mechanism which may be satisfactorily em-

ployed as part of the cutter actuating mechanism of the invention.

Fig. 5 is a diagrammatic view showing the manner in which the cylinder-piston mechanism may be connected in series with the control valve.

As shown in Figs. 1, 2, and 4, this preferred embodiment of our invention employs a body 10 consisting of a plurality of radial-
10 ly extending vanes or webs 11 which are of such radial dimension that their outer edges or faces 12 define a circle slightly smaller than the interior of a well casing or tubular member 13 in which the perforator is inserted
15 for the purpose of perforating a cylindrical wall thereof. The upper and lower ends 14 and 15 of the vanes 11 are sloped so as to define cones, and the upper and lower ends of the vanes join with axially extending upper
20 and lower bosses 16 and 17.

In the form of the invention shown, twelve of the vanes 11 are employed. Formed in the body integral with the vanes 11 adjacent thereto are a plurality of cylinders 20, 21, 22, 25, 23, 24, and 25, these cylinders being positioned one below the other, as best shown in Fig. 1, and each cylinder having a length substantially as great as the diameter of the body 10. The front end of each cylinder wall 20 to 25
30 is equipped with threads 26, as shown in Fig. 4, to receive an externally threaded, removable front plate 27, and each front plate 27 has an external flange 28 of vertically oval shape whereby to reduce the lateral dimension thereof and to provide opposing flat faces 30 which may be engaged by a wrench to screw or unscrew said plate 27 from said threads 26. The rear end of each cylinder has a closed rear wall 31 comprising a radially inwardly extending annular shoulder 32 having a shoulder opening 33 in which a plug 34 is set. The wall member 27 has an inwardly extending hub 35 provided with a recess 36 for holding packing 37 and having a gland 38 threaded therein for the purpose of compressing the packing 37. Extending within or through an axial bore 40 in the member 27 is a bar 41 having a diametrically reduced inner portion 42 on which a piston
45 43 is secured by means of a nut 44. The piston 43 may be made in any recognized form, but in this embodiment of our invention we employ a central annular member 45 against which cup washers 46 and 47 are held by
50 means of end plates 48 and 49, there being, if desired, a lock washer 50 between the end plate 49 and the nut 44.

The outer or front end of the bar 41 is provided with a transverse slot 53 adapted
60 to receive a tool 54 which in the present embodiment of our invention consists of a perforating blade or cutter of alloy steel. The tool 54 is held in operative position in the slot or recess 53 by a transverse pin, screw, or bolt 55. The piston 43 divides the

cylinder into a rear chamber 56 and a front chamber 57. By introducing fluid under pressure into the rear chamber 56, the piston 43 is impelled outwardly so as to cause the bar 41 to carry the tool 54 into operative engagement with the wall of the tubular member 13 and to cause the tool 54 to perforate the member 13, as indicated by dotted lines 58. By forcing fluid under pressure into the front chamber 57 and releasing the fluid from the rear chamber 56, the piston may be caused to move inwardly and retract the tool 54 from extended position to the withdrawn position in which it is shown in full lines in Fig. 4.

Associated with the body 11, and secured thereto by means of a threaded connecting member 60, is a valve body 61 having a threaded inlet opening 62, as shown in Fig. 3, into which the lower end of a string of pipe 63 may be threaded. In the leftwardly offset portion 64 of the body 61 is a vertical bore 65 having a perforated plug 66 threaded into the lower end thereof and being adapted to slidably receive a valve piston 67. The upper end of the bore 65 is counterbored and threaded, as indicated at 68, to receive a threaded double-end connector 70 to which an upwardly extending tube 71 is secured, this tube having a bored plug 72 threaded into the upper end thereof. A valve stem 73 extends upwardly from the valve piston 67 through the members 70, 71, and 72, and has a ring 74 formed at its upper end to which an actuating part in the form of a rope 75 may be secured. An annular plate or shoulder member 76 is secured intermediately on the valve stem 73 by means of a pin 77, and a compression spring 78 is placed between the plug 72 and the plate 76 so as to normally exert a downward pressure on the plate 76, which pressure is transmitted through the pin 77 to the valve stem 73 and tends to resiliently hold the valve piston 67 in the lowered position in which it is shown in Fig. 3. From the inlet opening 62 a fluid inlet passage 80 extends downwardly and then turns leftwardly, as indicated at 81, to communicate with the bore 65. Above the portion 81 of the inlet passage 80 is an expanding fluid passage 82 which turns rearwardly, as indicated at 83 in Fig. 3. Below the portion 81 of the inlet passage 80 is a retracting fluid passage 84 which turns forwardly, as indicated at 85 in Fig. 2. From the outer end of the retracting fluid passage 84, as shown in Figs. 1, 2, and 5, a fluid transfer pipe 86 extends to communication with the front chamber 57 of the cylinder 20, and, as best shown in Fig. 5, intercommunicating pipes 87 extend between the forward ends of the cylinders 20, 21, 22, 23, 24, and 25 and are in open communication with the front chambers 57 of the cylinders which they interconnect. From the outer end of the ex- 130

panding fluid passage 82, a fluid transfer pipe 88 extends to the rearward end of the cylinder 20 and through an opening 90 in the wall of the cylinder 20 communicates with the rear chamber 56 thereof. Between the rear ends of the cylinders 20, 21, 22, 23, 24, and 25, intercommunicating pipes 91 are extended, these pipes being in open communication with the rear chambers 56 in the cylinders which they interconnect. The pipes 86, 87, 88, and 91 are secured in place by having their ends welded into the openings provided therefor, in the manner shown at 92 in Fig. 2. As shown in Fig. 3, the valve piston 67 has an open space 93 therein of sufficient length to interconnect either the passages 80 and 84 or the passages 80 and 82. When no upward pull is exerted on the rope 65 and the spring 78 holds the valve piston 67 in its lowered position, as shown in full lines in Fig. 3, the space or passage 93 connects the inlet passage 80 with the passage 84 so that fluid under pressure delivered through the pipe 63, by which the perforator is also suspended in the tubular member 13, will be directed from the passage 80 through the space 93, the passage 84, and the transfer pipe 86, into the front chamber 57 of the upper cylinder 20. This fluid is also conducted through the intercommunicating pipes 87 into the front chambers 57 of each and all of the cylinders 21 to 25, thereby exerting against the front faces of the pistons 43 a pressure which will move the pistons into retracted position, as shown in full lines in Figs. 4 and 5, and there hold them. During this time, the expanding passage 82, which communicates with the rear chambers 56 of the cylinders through pipes 88 and 91, is connected through the upper portion 95 of the bore 65 and an outlet passage 96 with the exterior of the valve body 61, thus permitting fluid to flow freely from the rear chambers 56 of the cylinders as the pistons 43 are moved toward retracted position.

In the operation of the device, the body is lowered by means of the pipe 63 to a desired position within the tubular member 13. Fluid under pressure is then introduced through the pipe 63, and, by an upward pull on the rope 75 the valve piston 67 is moved into raised position, as indicated by dotted lines 98, thus causing the space 93 to connect the inlet passage 80 with the passage 82, whereupon fluid under pressure will flow through the passage 82 and the transfer pipe 88 into the rear chamber 56 of the upper cylinder 20 and then through the intercommunicating pipes 91 to the rear chambers 56 of the cylinders 21 to 25, the pressure of this fluid within the rear chambers 56 exerting a force against the rear faces of the piston 43 and operating or impelling them outwardly so as to move the perforating tools 54 into engagement and through the wall of the tubular

member 13, thus producing a perforating action of the device.

When the piston 67 is held in raised position, the lower end thereof, as indicated by dotted lines 100, is above the mouth of the passage 84, thus placing the passage 84 in open communication with the exterior through the lower portion 101 of the bore 65 and a relief passage 102 in the perforated plug 66, thereby permitting fluid to be discharged from the front chambers 57 of the cylinders 20 to 25 through the pipes 87 and 86 when the pistons 43 are impelled outwardly by fluid pressure in the rear chambers 56 of the cylinders.

On completion of this perforating action, the rope 75 is lowered so as to permit the spring 78 to carry the valve piston 67 into lowered position to again connect the inlet passage 80 with the retracting passage 84 whereby to introduce fluid under pressure to the front chambers 57 of the cylinders so as to cause the retraction of the pistons 43 and the tools 54 connected thereto and actuated hereby.

In Fig. 4, radiating arrows A, B, C, D, E, and F are shown. The angles between these consecutive and adjacent arrows are each 60°, and each arrow coincides with a vertical plane; therefore, since the arrows are equally spaced, the vertical planes in which they lie intersect the circle G represented by the inner wall of the tubular member 13 so as to divide such circle G into substantially equal parts. The arrows A, B, C, D, E, and F respectively indicate the lines along which the cylinders 20, 21, 22, 23, 24, and 25 guide or direct the pistons 43, bars 41, and tools 54 respectively associated therewith. Therefore, it will be seen that the six tools 54 have outward movement along lines spaced at substantially equal angles so that the forces exerted by such tools when they are in engagement with the tubular member 13 are distributed in such a manner that the tubular member 13 will not be deformed to oval shape as a result of the perforating operation.

Although we have herein shown and described our invention in simple and practical form, it is recognized that certain parts or elements thereof are representative of other parts, elements, or mechanisms which may be used in substantially the same manner to accomplish substantially the same results; therefore, it is to be understood that the invention is not to be limited to the details disclosed herein but is to be accorded the full scope of the following claims.

We claim as our invention:

1. In a device of the character described, the combination of: a body adapted to be inserted in a tubular member; a tool movably supported on said body so as to move to and from engagement with said tubular member;

hydraulically actuated means for forcing said tool into operative engagement with said tubular member and moving said tool from engagement with said tubular member; a 5 fluid delivery member for conducting fluid under pressure to said hydraulically actuated means; and valve means adjacent said hydraulically actuated means and connecting said fluid delivery member therewith, for determining the direction of movement of said tool.

2. In a device of the character described, the combination of: a body adapted to be inserted in a tubular member; a tool movably 15 supported on said body so as to move to and from engagement with said tubular member; hydraulically actuated means for forcing said tool into operative engagement with said tubular member and moving said tool from 20 engagement with said tubular member; a fluid delivery member for conducting fluid under pressure to said hydraulically actuated means; and control means adjacent said hydraulically actuated means and connecting 25 said fluid delivery member therewith, for determining the direction of movement of said tool, said control means having an actuating part extending outside said tubular member.

3. In a device of the character described, 30 the combination of: a body adapted to be inserted in a tubular member, said body having a wall forming a cylinder; a piston in said cylinder; a tool operatively connected to said piston; means for holding said body in a desired 35 position of operation in said tubular member, there being a fluid passage extending from said cylinder to the exterior of said tubular member; and valve means situated in proximity to said body and associated with 40 the lower part of said passage for controlling the flow of fluid to said cylinder.

4. In a device of the character described, the combination of: a body adapted to be inserted in a tubular member, said body having 45 a wall forming a cylinder; a piston in said cylinder; a tool operatively connected to said piston; means for holding said body in a desired position of operation in said tubular member, there being a fluid passage extending from said cylinder to the exterior of said tubular member; valve means situated in proximity to said body and associated with the lower part of said passage for controlling the flow of fluid to said cylinder; and an 55 actuating part extending from said valve means to the exterior of said tubular member, for actuating said valve means in a manner to accomplish control of the flow of fluid through said passage.

60 5. In a perforator of the character described, the combination of: a body adapted to be inserted in a tubular member, said body having a plurality of cylinders pointing radially outwardly at substantially equal angles; a piston in each of said cylinders; a

perforating tool associated with each of said pistons and adapted to be moved into operative engagement with said tubular member by the piston with which it is associated; means for holding said body in a desired 70 position of operation in said tubular member, there being a single fluid passage extending to said cylinders from a point outside said tubular member for carrying a fluid under pressure; and valve means situated in proximity to said body and associated with said passage for controlling the flow of fluid therethrough.

6. In a perforator of the character described, the combination of: a body adapted 80 to be inserted in a tubular member, said body having a cylinder; a piston in said cylinder; means for supporting said body within said tubular member; a perforating tool associated with said piston and adapted to be moved into operative engagement with said tubular member by the piston; walls forming 85 passages connecting with the front and rear ends of said cylinder; a four-way valve adjacent said body, said four-way valve being connected to said passages; and a duct extending from the exterior of said tubular member for delivering fluid under pressure to said four-way valve.

7. In a perforator of the character described, the combination of: a body adapted 95 to be inserted in a tubular member, said body having a cylinder; a piston in said cylinder; means for supporting said body within said tubular member; a perforating tool associated with said piston and adapted to be moved into operative engagement with said tubular member by the piston; walls forming 100 passages connecting with the front and rear ends of said cylinder; a four-way valve adjacent said body, said four-way valve being connected to said passages; a duct extending from the exterior of said tubular member for delivering fluid under pressure to said four-way valve; and actuating means 105 for said valve.

8. In a perforator of the character described, the combination of: a body adapted to be inserted in a tubular member, said body having a cylinder; a piston in said cylinder; means for supporting said body within said tubular member; a perforating tool associated with said piston and adapted to be moved into operative engagement with said tubular member by the piston; walls forming 115 passages connecting with the front and rear ends of said cylinder; a four-way valve adjacent said body, said four-way valve being connected to said passages; a duct extending from the exterior of said tubular member for delivering fluid under pressure to said four-way valve; and an actuating member for said valve extending from said valve to the end of said tubular member.

9. A perforator of the character described,

including: a body adapted to be inserted in a well casing; means for supporting said body in a desired position in said well casing; a fluid expandable member carried by 5 said body; a tool operatively connected to said expandable member; a fluid delivery member extending from the exterior of said well casing to said body; a valve at said body for connecting said delivery member to said 10 expandable member; means extending from said valve to the end of said casing for operating said valve to deliver fluid to said expandable member whereby said tool is forced into engagement with said casing; and means 15 for retracting said tool when said valve is returned to inoperative condition.

10. A perforator of the character described, including: a body adapted to be inserted in a well casing; means for supporting 20 said body in a desired position in said well casing; a fluid expandable member carried by said body; a tool operatively connected to said expandable member; a fluid delivery member extending from the exterior 25 of said well casing to said body; a valve at said body for connecting said delivery member to said expandable member; means for operating said valve to deliver fluid to said expandable member whereby said tool is forced 30 into engagement with said casing; and means for retracting said tool when said valve is returned to inoperative condition.

In testimony whereof, we have hereunto set our hands at Los Angeles, California, this 35 27th day of April, 1931.

ROSCOE MOSS.
HAROLD U. BAKER.
